AUTOMATIC CHOKE CONTROL FOR INTERNAL COMBUSTION ENGINES

August C. Purpura, Chicago, Ill.

Application December 5, 1931, Serial No. 579,144

20 Claims. (Cl. 123—119)

This application is a continuation in part of application #542,089, filed by me June 4, 1931 on an Automatic choke control for automobile engines.

5 My invention relates to means for automatically modifying the mixture of air and fuel supplied to an internal combustion engine, so as to secure an efficient mixture and to expedite the starting and speeding up of the engine regardless of 10 the temperature of the engine and of the outer air, and without requiring any skill on the part of the operator of the engine.

In one of its major aspects, my invention aims 15 to provide simple, inexpensive and entirely automatic means for choking the air intake of such a carburetor during the starting of the engine when the engine temperature is below a certain minimum, for regulating the extent of this initial choking according to the prevailing temperature 20 after the starting of the engine, and for entirely discontinuing the choking when the engine temperature has risen to a predetermined extent. Moreover, my invention aims to provide control 25 means for these purposes which also will increase the supply of fuel to the engine both during the starting of the engine when the latter is cold and during the warming-up period, and which will automatically discontinue this increase of 30 the fuel supply.

In an additional aspect, my invention aims to 35 provide an auxiliary control mechanism for the above recited purposes which can readily be attached as a unit to customary types of internal combustion engines, and particularly to those commonly employed on automobiles, without requiring any extensive drilling or machinery.

In this aspect, my invention aims to provide 40 a mechanism of the above recited characteristics which will automatically increase the idling adjustment of the fuel throttle of an automobile when the engine is cold, so as to prevent a stalling 45 of the vehicle in cold weather; which will eliminate fires due to a spitting of flame through a carburetor, and which also will prevent excessive gasoline consumption and excessive oil dilution by entirely eliminating the use of a hand-controlled choke.

In addition to affording these highly desirable 50 characteristics in its construction and functioning, my invention also aims to provide an automatic control mechanism of the above recited class, which will be independent of the usual starting switch and which will not necessarily require any supply of electric current; thereby permitting my choke control to be used to equal

advantage on magneto-equipped and hand-cranked auto trucks, and also preventing any drain on the more customary battery of a car equipped with an electric starter at the very time when the full capacity of the battery may be required for operating the starter.

Furthermore, my invention aims to provide an auxiliary air and fuel supply control mechanism for the above recited purposes which will be low in cost of manufacture and which can readily be attached as a unit to customary types of internal combustion engines, and particularly to the types commonly employed on automobiles, without requiring any extensive drilling or machining.

Still further and also more detailed objects of 70 my invention will appear from the following specification and from the accompanying drawings, in which drawings

Fig. 1 is an elevation of an embodiment of my invention connected to a carburetor, air inlet and manifold inlet, showing the mechanism as it 75 appears after the engine has been started and before the engine has warmed up.

Fig. 2 is an enlarged and fragmentary horizontal section, taken along the line 2—2 of Fig. 1, with the leg portions of the suction-cylinder-supporting base omitted.

Fig. 3 is a view similar to a portion of Fig. 1, showing the position of different portions of the mechanism when the engine has warmed sufficiently for reducing the suction in the larger 85 control cylinder.

Fig. 4 is a view of the same parts taken when the engine is running at normal warmth.

In the embodiment of the drawings, the flow 90 of air through the intake pipe 1 of Fig. 1 is controlled by a damper 2 fastened to the shaft 3 of a rocking lever 4. This lever has one of its oppositely directed arms connected respectively by a link 5 to the rod 6 on a piston 7 which slides in a cylinder 8; while the other lever arm is connected by a second link 9 to the rod 10 on a second piston 11. This second piston 11 is slidable in a cylinder 12 which is considerably larger in bore than the cylinder 8; and the link 9 associated with the said second piston has a longitudinal slot 13 through which a pin 14 on the lever extends, whereby this slot permits a limited lost motion between the lever or rocking arm 4 and the larger diametered piston 11.

The outer end of the smaller-diametered cylinder 8 is connected to the manifold 31 by a suction pipe 15 which maintains a continuously open connection to that cylinder, so that the smaller diametered piston 7 is always subject to the suc-

tion in the manifold when the engine is running. The manifold is also connected to the outer end of the larger-diametered cylinder through a suction pipe 16, but the suction through this type is 5 automatically controlled according to the temperature of the manifold.

For this control purpose I am here showing a 10 tapered valve member 17 mounted on one end of a bimetallic strip 18 disposed within the manifold and fastened at its other end to the latter; the arrangement of the two metals being such that this strip will be flexed away from the inlet of the suction pipe 16 when cold (so as to open the inlet of the latter pipe as in Fig. 1), but will 15 be flexed toward the said inlet when the intake pipe is heated, so as to close the inlet of the suction pipe 16 as in Fig. 3.

Both of the piston rods 6 and 10 slide through 20 a base member 20 seated upon and fastened to the exterior of the intake pipe 1 so that portions of this member serve as the inner heads of the two cylinders. Interposed between this base member and the rocking lever 4 is a spiral tension spring 21 which is disposed so that the axis of 25 the spring will pass across the axis of the lever shaft 3 when the lever moves from the cold starting position of Fig. 1 to the normal running position of Fig. 3, and vice versa.

Extending into the larger diametered cylinder 30 12 through the outward end 12A of the latter is a stop screw 22 which desirably extends axially of the cylinder and is disposed for engaging the larger piston 11 to limit the outward (or valve-opening) movement of that piston. This stop screw is connected to a stationary member, such as a riser screw 23 on the piston head 12A by a coiled bimetallic strip 24 which has its two metal portions disposed so that the screw will be rotated for advancing it into the cylinder 12 when the 40 said coiled strip warms up, and for moving the tip of the screw farther from the base member 19 when the coiled strip cools. Thus arranged, this bimetallic coil automatically moves the stop screw 22 in response to the temperature around the said 45 coil exteriorly of the cylinders, and hence according to the temperature of the air under the hood of an automobile when my control mechanism is used in connection with an automobile engine, so as to vary the extent to which the slot 50 13 in the link 9 will permit lost motion between the valve and the larger diametered piston 11.

With the mechanism thus arranged, the uninterrupted suction through the suction pipe 15 during the running of the engine continuously 55 tends to lift the smaller piston 8; and when the manifold 31 is hot so that the valve member 17 shuts off the suction in the larger diametered cylinder 12, this lifting action on the smaller piston 7 holds the parts as shown in Fig. 4. In 60 this position, the larger piston 11 is halted by the engagement of a pin 6A on the piston rod with the base member 19; the lever pin 14 is at the outer end of the slot 13 in the link 9; and the spring 21 assists the smaller piston in holding the 65 valve 2 open so as to permit the maximum flow of air through the pipe air-inlet 1, which pipe may be one of a plurality of intakes for the associated carburetor, according to a common custom.

If the engine is then stopped, the suction 70 through the suction pipe 15 ceases, but the throw-over spring 21 will continue to hold the air valve 2 in its full open position as shown in Fig. 4; and if the engine is restarted while the intake is still sufficiently hot for keeping the suction-controlling valve 17 on its closure position, my mecha-

nism will not be actuated in any manner during this starting.

However, if the engine has cooled sufficiently while idle, so that the thermostatic suction-controlling valve 17 has opened, a starting of the engine will initially create a suction in both cylinders, with the following effect: Owing to the difference in diameters of the two pistons, these will exert oppositely directed and unequal pulls on the rocking lever 4; and with the spring 21 of a tension exerting less effort on the lever than the difference between the pulls of the two pistons, the lifting action on the larger diametered piston 10 overpowers the combined action of the smaller piston 7 and the spring. Consequently, the starting of the engine will rock the lever 4 (in a counterclockwise direction from the running position of Fig. 4) to the position of Figs. 3 and 4, in which the larger-diametered piston 11 is halted by engaging the stop screw 22.

In other words, the differential suction action acts through the two links 5 and 6 to rock the lever until the throw-over spring 21 snaps past the axis of the lever shaft 3 and the larger piston is halted by the stop screw 22 (or to a position 100 in which the intake is only partly closed); and the pull of the spring 21 then completes the closing of the valve by a further movement (to the position shown in Fig. 1), this additional movement of the lever in the valve-closing direction being permitted by the slot 13 in the link 9. Since the outward movement of the larger piston is limited by the thermostatically controlled stop screw 22, the extent of this additional movement of the valve is varied according to the temperature around the mechanism, so that the valve will be closed to a less extent during the initial action of my mechanism at the starting of the engine during cold weather than at warm prevailing temperatures.

The rocking lever 4 which moves the air-control valve 2 is desirably also connected to the usual fuel valve 26, as for example by a connection to the usual valve-operating lever 27 which is actuated by the throttle rod 37. For this purpose I am showing a link 48 pivoted at one end to the rocking lever and having in its other end a longitudinal slot 28 in which a pin 29 on the valve lever 27 is slidable. This slot is of such length and position that its ends are out of engagement with the pin 29 during the operation of my mechanism whenever the throttle rod 37 is in its normal inoperative position, as shown in the drawings. However, if this rod is slid forward (by its usual manual operation from the dashboard of the car) so as to open the fuel valve 26 during the starting of the car, the pin 29 will engage the forward end of the slot in the link 28 so as to move this link forwardly and downwardly, thereby correspondingly opening the air valve 2 also.

Thus arranged, this connection to the fuel valve of the carburetor causes the supply of fuel to be increased automatically whenever the major piston 11 is initially drawn up against the stop screw 22. Then, if the engine spits during its starting, the lost motion between the link 9 and the rocking lever permits the resulting back pressure in the smaller cylinder to rock the lever 27, thereby causing the lever to open the fuel valve still more, so as to overcome the leaness of the mixture which caused the spitting. And since the just described effect of the so-called "spitting" momentarily closes the air control valve 2, the back firing cannot cause flames to 150

issue through the air inlet, so that my mechanism automatically prevents the fires due to this cause.

During the warming up of the engine, the intake manifold of the carburetor rises in temperature also, thereby causing the thermostatic strip 18 to flex so as to gradually move the valve member 17 toward its closure position and hence reducing and finally entirely discontinuing the suction in the larger cylinder 12. This cessation of suction in the larger cylinder allows the larger piston 11 to drop by gravity, so that its weight assists the uninterrupted suction on the smaller piston in tending to rock the lever 4 (against the resistance of the spring 21) for opening the air valve. As soon as the suction in the smaller cylinder 8 becomes sufficient for this purpose, the piston 7 rises and snaps the spring 21 past the axis of the valve and lever shaft 3, whereupon the spring cooperates with this piston in raising the latter to the position shown in Fig. 1, in which position the valve 2 is fully open and the fuel-valve opening thrust of the rod 26 is relaxed.

When the engine is then stopped, the suction in the smaller cylinder 8 is discontinued, but the spring 21 continues to hold the air valve open, so that my choke mechanism is inoperative if the engine is again started while the intake manifold is still warm. However, if the engine has cooled before it is restarted, the thermostatically controlled valve member 17 will open the suction duct to the larger cylinder, so that my mechanism will again operate according to the previously described cycle.

Since a starting of the engine always produces an intake suction, my mechanism is obviously independent of the means employed for the starting. Consequently, its operativeness is not affected by the condition of any battery or starting mechanism, and requires no electrical connections. Moreover, entire operation is entirely automatic, thereby eliminating the need of a hand-operated choke control which so often leads to a flooding of the carburetor. This automatic action even includes the adjustment for exterior temperature conditions, and also includes an automatic opening of the fuel valve to a wider extent than that afforded by the adjustment of the carburetor, thereby modifying the so-called idling adjustment so as to prevent a car equipped with my control mechanism from stalling in traffic, during the warming up period.

However, while I have heretofore described an embodiment of my invention which includes both the auxiliary fuel-supply control and a temperature-responsive stop adjustment for regulating the extent to which the air-intake valve is closed, I do not wish to be limited to the conjoint use of these auxiliary features. Both of these might be omitted but are desirably employed also, because the stop adjustment (when suitably proportioned) makes my control substantially independent of the prevailing weather conditions in its responsiveness; and because the auxiliary fuel valve-control insures the temporary increasing of the fuel when this is needed, but prevents a continuing of this increasing when no longer required.

So also, while I have illustrated my automatic control mechanism somewhat diagrammatically in a simple embodiment including two suction cylinders of relatively different diameters and including a rocking lever directly mounted on the shaft of the air-intake valve, I do not wish to be limited to these or other details of the construction and arrangement thus disclosed, since many

changes might be made without departing either from the spirit of my invention or from the appended claims.

For example, instead of making the two suction cylinders and their pistons of relatively different diameters and connecting them to lever arms of equal length, I may make the cylinders equal in diameter and connect them to oppositely directed lever arms of unequal length, as shown in Fig. 3. In this case, the effective pull on each piston will be the same when the suction ducts to both cylinders are open, but the thrust exerted by the piston in the cylinder 12A will have a greater effect on the rocking lever 4A than that in the continuously suction-connected companion cylinder. In either case, the intake valve is connected to two oppositely acting suction means, the more powerfully effective of these means has its suction controlled in response to the temperature of the intake manifold.

Since the temperature of this pipe varies with that of the engine, the control of the suction in the effectively weaker suction-actuated means is responsive to variations in the temperature of the engine. Hence it will also be obvious that the position of the temperature-responsive element 18 and of the valve controlled by it may be varied, so long as the said element is influenced by changes in the temperature of the engine.

Moreover, the operation of my control mechanism will obviously be the same regardless of the purpose served by the engine or the like to which my mechanism is applied, so that my invention will be equally applicable for use in connection with engine driven pumps, hoists or other devices. Hence I do not wish to be limited as to the nature of the device on which my invention is employed, although it is particularly suitable for use on automobiles.

In the illustrated embodiment, I have shown the two suction cylinders as mounted on a base plate 29 which seats upon and is fastened to the air intake pipe 19 between the air filter 41 (at the inlet end of the air intake) and the mixing chamber 42 to which both the float chamber 43 and the air intake are connected. In Fig. 1 I have also pictured the suction-controlling thermostatic member 18 and the adjacent end of the suction pipe 16 as fastened to a gasket 44 which is clamped between the usually adjacent flanges on the carburetor and the intake 31 of the manifold, thus showing how easily my invention may be adapted for use without changes in any part of the engine.

In the claims, it is to be understood that the words "closing" and "closure" are used in a relative sense, since the movable valve member which controls the air intake may be formed so that it merely throttles that intake when the engine has only a single air intake, or may be formed so as to close the intake entirely when the engine also has an additional air intake.

I claim as my invention:

1. An air intake control mechanism for an internal combustion engine having an air intake duct, comprising: a movable valve member controlling the said duct; of intake-closing means responsive to the running of the engine for moving the said member toward its closure position; 115 separate and relatively weaker means responsive to the suction of the engine, for urging the said member away from its closure position; and means responsive to the temperature of the engine for annulling the operation of the intake- 150

- closing means when the said temperature is above a predetermined minimum.
2. An air intake control mechanism as per claim 1, including spring means tending to hold the valve member in its closure position after the valve member has been moved to a certain extent toward that position by the intake-closing means.
3. An air intake control mechanism as per claim 1, including spring means tending to hold the valve member in its closure position after the valve has been moved to a certain extent toward that position by the intake-closing means, the intake-closing means being operatively stronger than the spring means.
4. An air intake control mechanism as per claim 1, including spring means tending to hold the valve member in its closure position after that member has been moved to a certain extent toward that position by the intake-closing means, the spring means being so disposed that it also cooperates with the said stronger means for tending to hold the said member in its valve-opening position when the operation of the intake-opening means has been annulled by the last named means.
5. An air intake control mechanism as per claim 1, including a lost-motion connection between the said valve-member and the intake-closing means.
6. An air intake control mechanism as per claim 1, including auxiliary temperature-responsive means for varying the extent to which the valve member is movable towards closure position.
7. An air intake control mechanism for an internal combustion engine having an air intake duct, comprising: a movable valve member controlling the said duct; intake-closing means operative when the engine temperature is below a predetermined minimum, for moving the said member part way toward its closure position when the engine is started; spring means moving the valve member further in the intake-closing direction after the valve member has been moved part way by the intake-closing means, and suction-actuated means responsive to the intake suction of the engine and connected to the said member so that the said suction tends to move the valve member in the intake-opening direction; the spring means being of insufficient strength for alone resisting the intake-closing means when the said suction-actuated means are inoperative.
8. An air intake control mechanism as per claim 7, in which the spring means are arranged for resisting the movement of the valve member away from its closure position during only a part of the permitted movement of the said member.
9. An air intake control mechanism for an internal combustion engine having an air intake duct, comprising: a movable valve member controlling the said duct; valve-closing means responsive to the running of the engine for moving the said member part way toward its closure position; movement-completing means, operating after the said member has been moved to a predetermined extent in the said direction by the valve-closing means, for completing the movement of the said member in that direction; valve-opening means responsive to the suction of the engine, for urging the said member away from its closure position; and means responsive to the temperature of the engine for annulling the operation of the valve-closing means when the said temperature is above a predetermined minimum.
10. In an internal combustion engine, a carburetor having an air intake duct, a movable valve member controlling the said duct; two valve-operating means of relatively different strength both responsive to the suction in the manifold of the engine; oppositely acting connections between the valve member and the said means, the connections being so arranged that the stronger means tend to close the valve and the weaker means tend to open the valve; and means associated with the stronger means for annulling the suction thereon under predetermined operating conditions of the engine.
11. In an internal combustion engine, a manifold, a carburetor connected to the manifold and having an air intake duct; a movable valve member controlling the said duct; two valve-operating means of relatively different strength both responsive to the suction in the manifold of the engine; oppositely acting connections between the valve member and the said two means, the connections being so arranged that the stronger means tend to close the air intake and the weaker means tend to open the air intake; and means associated with the stronger means for annulling the suction thereon when the temperature of the engine exceeds a predetermined minimum.
12. An air intake control mechanism for an internal combustion engine, as per claim 11, including temperature-responsive means for automatically varying the extent to which the said valve member can be moved by the said stronger means.
13. An air intake control mechanism for an internal combustion engine, as per claim 11, including temperature-responsive means for automatically varying the extent to which the said valve member can be moved by the said stronger means, the temperature-responsive means including a thermostatic member disposed exteriorly of the engine.
14. An air intake control mechanism as per claim 10, including a throw-over spring operatively connected to the valve member for assisting either the stronger or the weaker of the said means according as the valve is opened respectively more or less than to a predetermined extent.
15. The combination with the air intake duct and the manifold of an internal combustion engine, of a movable valve member controlling the said duct, two differently diametered cylinders each connected at one end to the manifold, a piston slideable in each cylinder, a rocking lever fast with respect to the valve and having oppositely directed arms respectively connected to the two pistons; and a thermostatic valve associated with the connection of the larger diametered cylinder to the manifold for controlling the said connection so as to discontinue that connection after a predetermined rise in temperature, and so as to restore that connection when the temperature falls below a predetermined minimum.
16. An air intake control mechanism as per claim 15, including a link interposed between the larger diametered piston and the rocking lever, the link having a slot affording a lost motion connection between the lever and the larger diametered piston.
17. In an internal combustion engine having an air intake and a manifold, an automatic control mechanism including a movable valve member controlling the said intake; two cylinders connected to the manifold; two pistons of relatively

- different diameter slidable respectively in the said cylinders and both subject to the suction of the engine when the engine is being started and the engine temperature is below a predetermined maximum; connections between the said valve member and the two pistons whereby the suction on the larger piston tends to move the said member in its closure direction, and whereby the suction on the smaller piston tends to move the said member in its intake-opening direction; and means responsive to a rise in the temperature of the engine beyond the said maximum for discontinuing the suction through the cylinder associated with the larger piston.
- 15 18. In an internal combustion engine, a control mechanism as per claim 17, in which the connections include a rocking lever fast on the movable valve member and having oppositely directed arms respectively connected to the two pistons; and a throw-over spring connected to the lever and assisting either one of the pistons according to whether the valve is opened more or less than a predetermined extent; the connection between the lever and the larger diametered piston being arranged to afford lost motion for permitting the spring to move the valve member, in the direction in which that member is moved by the larger piston, to a greater extent than to which the larger diametered piston moves the said member.
- 20 19. In an internal combustion engine, a control mechanism as per claim 17, in which the connections include a stop member mounted on the larger diametered cylinder for limiting the extent to which the piston in that cylinder can be moved by suction, and temperature-responsive means for varying the effective position of the stop member.
